[57] CLAIM

The ornamental design for an electric clock or similar article, as shown and described.

DESCRIPTION

FIG. 1 is a front elevational view of an electric clock or similar article showing our new design;

FIG. 2 is a top plan view thereof, the bottom plan being a mirror image thereto;

FIG. 3 is a rear elevational view thereof; and

FIG. 4 is a right side elevational view thereof, the left side being a mirror image thereto.
